UNITED STATES PATENT OFFICE

121,807

DESIGN FOR A REMOVABLE BOTTLE STOPPER

Ferdinand E. Fender, Evanston, Ill., assignor to
Vaughan Novelty Manufacturing Company,
Chicago, Ill., a corporation of Illinois

Application May 2, 1940, Serial No. 92,093

Term of patent 14 years

To all whom it may concern:

Be it known that I, Ferdinand E. Fender, a citizen of the United States, residing at Evanston, in the county of Cook and State of Illinois, have invented a new, original, and ornamental Design for a Removable Bottle Stopper, of which the following is a specification, reference being had to the accompanying drawing, forming part thereof.

Figure 1 is a perspective view of the removable bottle stopper embodying my new design.

Fig. 2 is a top plan view thereof.

Fig. 3 is a front elevation thereof.

Fig. 4 is a side elevation thereof.

I claim:

The ornamental design for a removable bottle stopper, as shown.

FERDINAND E. FENDER.
